TABLE

John R. Dresser, Libertyville, Ill., assignor to The Chicago Hardware Foundry Company, North Chicago, Ill., a corporation of Illinois

Filed Mar. 15, 1965, Ser. No. 84,274

Term of patent 3½ years

(Cl. D33—14)

FIG. 1 is a perspective view of a table showing my design;

FIG. 2 is a side elevational view showing the base on an enlarged scale and with portions of the table omitted for convenience of illustration;

FIG. 3 is a plan view of the base of FIG. 2, and

FIG. 4 is an end view thereof.

The dominant features of my design reside in the base portion shown in full lines on the drawing.

I claim:

The ornamental design for a table, as shown and described.
